(57) CLAIM

The ornamental design for a seat, as shown and described.

DESCRIPTION

FIG. 1 is an isometric view of the seat of my design;

FIG. 2 is a top plan view.

FIG. 3 is a front elevational view.

FIG. 4 is a left side elevational view, the right side elevational view being a mirror image thereof;

FIG. 5 is a back elevational view.

FIG. 6 is a bottom plan view; and,

FIG. 7 is an isometric view of the seat of my new design, the only difference from FIG. 1 being the broken line showing of side arms.

The broken line showing in the drawing figures is for illustrative purposes only and forms no part of the claimed design.
